UNITED STATES PATENT OFFICE.

HENRY L. DE ZENG, OF GENEVA, NEW YORK, ASSIGNOR TO DE ZENG STANDARD COMPANY, OF CAMDEN, NEW JERSEY, A CORPORATION OF NEW JERSEY.

DIAGNOSTIC INSTRUMENT.

Application filed August 29, 1924. Serial No. 734,876.

To all whom it may concern:

Be it known that I, HENRY L. DE ZENG, a citizen of the United States, residing at Geneva, in the county of Ontario and State 5 of New York, have invented certain new and useful Improvements in Diagnostic Instruments, of which the following is a specification.

This invention relates to improvements 10 in diagnostic instruments and has particular reference to that type of instrument having self-contained illuminating means for projection of a beam of light through a lens system.

15 Prior to my invention, diagnostic instruments having self-contained illuminating means have been in general use, but all of them have embodied certain inherent defects. The principal defect has been due to the 20 fact that in the manufacture of incandescent bulbs used in such devices, variations occur in the position of the filament so that the filament is not centered in the center of the lamp butt. The result is that when a 25 bulb with these inaccuracies is positioned in an electric socket, the filament will not be in line with the usual light passage way extending from the socket. Since most of such instruments have their light passage 30 way provided with a condensing lens system and since the efficiency of the bulb is greatest at the center of the filament, it is very desirable that the center of the filament should be in line with the axis of the lens 35 system. This has been impossible in prior art instruments and as a result, the beam of light coming from the condensing lens system has not been uniform throughout its area. Furthermore, the beam of light in 40 the old instruments has not been sufficiently intense to permit of the efficient use of light filters or screens.

I would also call attention to the fact 45 that a great many diagnostic instruments, particularly ophthalmoscopes are provided with a reflecting surface having an elongated sight opening. Usually the reflector is made from two pieces slightly spaced apart, and the operator in using the instrument sights 50 through the space so formed. I have found that the utility of such an instrument is greatly improved by providing means whereby the bulb filament may be positioned in a plane substantially at right an-

gles to the plane of the elongated sight opening.

One of the principal objects of my invention is to provide an improved diagnostic instrument having a self-contained illuminating means so mounted that it may 60 be selectively moved transversely in relation to the light passage way.

Another object of my invention is to provide such an improved diagnostic instrument with an electric socket for holding an 65 incandescent bulb, said socket universally movable, to compensate for variations in the bulb manufacture.

Another object of my invention is to provide such a device with an electric socket 70 movable in a ball joint whereby the center of the bulb filament may be positioned in alignment with the sight opening and the condensing lens system.

Another object of my invention is to provide such a device with a light passage way and a condensing lens mounted therein, the position of the condensing lens being variable in relation to the illuminating means.

Another object of my invention is to provide such a device with an adjustably mounted incandescent lamp and a condensing lens system in line therewith the lens system being adjustable for the proper focusing of the light for the different positions of the lamp.

Another object of my invention is to provide a diagnostic instrument of this general character with a light filter or screen 90 which may be readily interposed in the path of light and conveniently moved out of operative position as desired.

Another object of my invention is to provide such a device with a plurality of screens any one of which may be positioned 95 for use independently of the others.

Another object of my invention is to provide a device of this character with improved means for connecting to a source of electric current.

Another object is to provide such a device with a handle member having means for receiving a detachable electric plug, and improved connecting means extending through the handle to a source of light.

Still another object of my invention is to provide such an instrument which will be simple in construction, strong and durable in

service, economical to manufacture, and an improvement in the art.

With these and other objects in view, the invention resides in the novel features of 5 construction, combination and arrangement of parts hereinafter fully described, illustrated in the accompanying drawings and specifically pointed out in the appended claims.

- 10 In the accompanying drawings forming a part of this application, Figure 1 is a front elevation of an ophthalmoscope embodying my invention. Figure 2 is a vertical, longitudinal sectional view through the same. 15 Figure 3 is a transverse sectional view on the line 3—3 of Figure 1. Figure 4 is a top plan view and Figure 5 is a horizontal sectional view on line 5—5 of Figure 1. Figure 6 is a section on line 6—6 of Figure 2. 20 Referring now to the drawings wherein similar reference characters are used to designate similar parts throughout the several views, the reference character 10 designates a handle member which is preferably made 25 of some insulating material such as hard rubber, and provided at its upper end with a metallic sleeve 11 having a center seat 12. The seat 12 is preferably of a spherical curvature for the reception of a ball joint 13, also 30 spherically curved on its exterior surface. Co-operating with the sleeve 11 above the seat 12 is a locking ring 14 which may be screwed into place in the extremity of the sleeve to clamp the ball joint 13 against the 35 spherical seat 12.

The upper extremity of the sleeve 11 is preferably screw threaded to which is secured a tubular member 15 which forms a housing for an illuminating means carried 40 by the ball joint 13. The tubular member 15 is preferably provided with diametrically opposed openings 16 for the ready manipulation and inspection of parts as will be hereinafter pointed out. Rotatably mounted 45 upon the housing 15 is another tubular member 17 which has diametrically opposed openings 18 and preferably a knurled portion 19 to facilitate an easy rotation. It will be noted that in Figures 1, 3 and 5, the 50 member 17 is illustrated in such a position as to close the openings 16, whereas in Figure 2, the openings 16 and 18 are shown in alignment.

The ball joint 13 has a central bore 20 55 which is here shown as being screw threaded for the reception of the butt 21 of an incandescent bulb 22. This bulb is provided with a filament 23 and a center contact 24.

Carried by the housing 15 is an insulation 60 washer which carries a tubular extension 25 which has a central longitudinal opening forming the light passage way 26. The lower end of the extension 25 is equipped with a sliding sleeve 27 having suitably fastened 65 therein the condensing lenses 28. Substan-

tially midway of its length and at one side the member 27 is screw threaded for the reception of a locking screw 29 having a suitably roughened or knurled head 30 for its easy manipulation. This locking screw 29 extends through a slot 31 in the side of the tubular member 25, whereby the lens carrying member 27 may be moved longitudinally of its axis and locked in any desired adjusted position. At its upper end, the light passage 70 way is provided with another condensing lens 32 which is here shown as being of a smaller diameter than the lens 28, but which obviously may be of any size or surface curvature desired. 75

At the upper end of the light passage way is a suitable flange 33 provided with threaded apertures on opposite sides of the lens 32, said apertures being adapted to receive the screws 34 which form pivots for lens carrying rings 35. The rings 35 have suitably mounted therein films or lenses 36 which preferably have certain light absorbing characteristics so that they may act as light filters or screens. Each of the members 36 has a different property and is so designed that either one may be selectively used for making different types of diagnostic observations. 80

Secured by any suitable means to the tubular extension 25 is a plate 37 which forms one side of a lens housing 38 in which is rotatably mounted a pair of lens carrying disks 39. The disks 39 carry a plurality of lenses 40 as is well known to those skilled in the art, each of these lenses having a different focal value. The plate 37 and housing 38 are provided with sight openings 41 substantially aligned with the axis of the condensing lenses 32 and 28 (see Figures 1 and 2). On the front side of the plate 37 and directly above the light passage way is an angularly disposed reflector which is preferably made of the two parts 42 and 43 slightly spaced apart as at 44 so that the operator when using the instrument may sight through the reflector. Because of the fact that the reflector is made of two parts with a space between them, it will be readily apparent that the sight opening so produced will be of elongated form as clearly shown. 90

Referring particularly to Figure 2, it will be seen that the handle member 10 is centrally bored as at 45 for the reception of a metallic tube 46 which contacts with one terminal 47 of the electric connection plug 48. Inside the metallic tube 46 are the bushings 49 and 50 of insulating material in the center of which is a post 51 which is engaged by the second contact 52 of the attachment plug 48. A transverse hole 53 contains a compression spring 54 which makes contact between the tubular member 46 and the sleeve 11, whereby the electric current is transmitted to the socket 13 forming one 100 115 120 125 130

side of the circuit which supplies energy to the illuminating bulb 22. The upper extremity of the post 51 is provided with a resiliently mounted plunger 55 which has an 5 enlarged end 56, the upper side of which is spherically curved and concave for contact with the center 24 of the lamp butt 21. Of course it will be understood that the center 24 is properly insulated from the butt 21 and 10 that one end of the filament 23 is connected to the member 21 while its other end is connected to the center 24, as is the usual practice.

The lower end of the tubular member 45 15 is slotted as at 57 (see Fig. 6) so as to give it sufficient resiliency to tightly clamp the plug member 47. The lower end of the post 51 is also slotted as at 58 so it will make good contact with the central terminal 52 of the 20 plug 48.

As has been previously pointed out, certain variations occur in the manufacture of incandescent bulbs whereby the position of the center of the filament varies. With my 25 construction I insert a bulb 22 in the ball joint or socket 13; then I loosen the clamp nut 14 and move the member 13 either laterally, transversely, or both as desired, so as to align the center of the filament with the 30 axis of the condensing lenses 28 and 32. In this way, the lenses will properly transmit the full light from the bulb 22. At the same time as this adjustment is being made, the socket 13 may be easily rotated about its 35 vertical axis so as to position the filament in a plane transverse to that of the sight opening 44, as is clearly shown in Figure 2. When these positions have been obtained, the lock ring 14 is screwed down so as to hold 40 the bulb firmly in the desired position, after which the condensing lenses 28 are adjusted through the instrumentality of the screw 29 and knurled head 30 so as to properly focus the light to give the desired result.

The instrument may be used with a clear light for making certain types of observations. In this case both of the light filters 36 are out of operative position as shown in Figure 2. If it is desired to absorb certain 50 of the light rays one of the screens 36 is moved into operative position by swinging its carrying ring 35 about the pivot 34 as will be easily appreciated from the construction illustrated and described. The technical use of the instrument is sufficiently well known to those skilled in the art and a more complete description of its operation is not deemed necessary in this application since the use of the rotatable lens carrying plate 55 40 is not new and furthermore since the invention is not to be confined to this particular type of instrument. While I have illustrated and described my invention as embodied in an ophthalmoscope, I desire it 45 to be strictly understood that it is equally

applicable to other instruments such as a retinoscope, otoscope, etc. Furthermore it will be obvious that modifications may be made in the details of construction and arrangement of parts and I herein reserve the 70 right to make such changes without departing from the spirit of my invention and the scope of the subjoined claims.

Having thus described my invention, I 75 claim:

1. In a device of the character described, an adjustably mounted illuminating means, a light passageway extending therefrom, a lens disposed in the passageway, and means for longitudinally moving the lens to compensate for adjustment of the illuminating means.

2. In a device of the character described, an illuminating bulb, a light passageway extending therefrom, a lens disposed in the passageway, means for adjusting the illuminating bulb laterally relative to the light passageway, and means for adjusting the lens longitudinally to compensate for the adjustment of the bulb.

3. In a device of the character described, a handle provided with a ball socket, an electric lamp mounted in the socket, a light passageway extending therefrom, a condensing lens disposed in the passageway, and means for longitudinally adjusting the lens in the passageway.

4. In a device of the character described, the combination with a universally movable lamp socket, of a yieldable center contact cooperating therewith, said center having a spherical surface disposed toward the socket.

5. In a device of the character described, a support, a universally movable socket therein, a lamp carried by the socket, and a yieldable contact post mounted on the support in line with the socket.

6. In a device of the character described, a support, a universally movable socket therein, a lamp centrally mounted in the socket, a yieldable post carried by the support and disposed toward the socket and a concave contact surface on the extremity of the yieldable post.

7. In a device of the character described, a handle, a lamp receiving socket carried by one end thereof, a metallic tube extending through the handle, one end of said tube having connection to the socket and the other end being adapted to receive and contact with the exterior of a detachable plug, a metallic post disposed within the tube and insulated therefrom, the plug end of said post being adapted to receive the central pole of the detachable plug, and a yieldable plunger mounted in the socket and of the post.

8. In a device of the character described, a handle, a lamp receiving socket carried

by one end thereof, a metallic tube extending through the handle, one end of said tube having connection to the socket and the other end being adapted to receive and contact with 5 the exterior of a detachable plug, a metallic post disposed within the tube and insulated therefrom, the plug end of said post being adapted to receive the central pole of the detachable plug, and the other 10 end to make central contact with the lamp.

9. In a device of the character described, a handle having a longitudinal bore, a lamp receiving socket attached to the upper end thereof, a metallic tube mounted in the bore 15 and having its upper end connected to the socket, a metallic post disposed within the tube and spaced from the walls thereof, the lower end of the post having a recess and a spring pressed plunger mounted in the 20 upper end of the post.

10. In a device of the character described, a handle having a longitudinal bore, a lamp receiving socket attached to the upper end thereof, a metallic tube mounted in the bore 25 and having its upper end connected to the socket, a metallic post disposed within the tube and spaced from the walls thereof, the lower end of the post having a recess, a spring pressed plunger mounted in the upper 30 end of the post, and a concave spherical head on the plunger.

11. In a device of the character described, a light, a light passage way for conducting the light-rays, a support at the side of the 35 passage way, and a lens cell pivoted on the support and adapted to be swung on its pivot into or out of alignment with the light rays in the light passage way.

12. In a device of the character described, 40 a light, a light passage way for conducting the light rays, a support on each side of the passage way, and a lens cell pivoted on each support and adapted to be swung on its pivot into or out of alignment with the light 45 rays in the light passage way.

13. In a device of the character described, a light, a light passage way for conducting the light rays, a slide in the passage way, a lens in the slide, and means for moving the slide longitudinally of the passage way. 50

14. In a device of the character described, a light, a light passage way for conducting the rays of light, having a longitudinal opening, a slide in the passage way, a lens in the slide, and a member projecting from the 55 slide through the longitudinal opening in the passage way, whereby the slide may be moved longitudinally of the passage way.

15. In a device of the character described, a light and a light passage way for conducting the light rays, comprising a tube in two sections detachably united, a lens adjacent the end of one of the sections, a slide in the other section, a lens in the slide, and means to move the slide longitudinally. 60

16. In a device of the character described, a handle having a spherical socket and openings in the walls, a spherical member seated in the socket, a lamp in the spherical member, and a cover having openings rotatably held on the handle whereby the openings in the cover may be made to align with the openings in the handle to expose the lamp and the solid portions of the cover made to cover the openings in the handle to hide the 75 light. 70

17. In a device of the character described, a handle, a tube on the handle having a spherical seat, peripheral openings and a screw threaded portion near the seat, a ball member having a socket for the lamp seated in the spherical seat, a ring in the tube having a portion adapted to fit over the ball member, and a threaded portion adapted to engage the threaded portion of the tube 85 whereby the ball member may be tightened or loosened in the seat and the lamp tightened or loosened in the ball member through the peripheral openings in the tube. 80

HENRY L. DE ZENG.
